TRAVELING TOY

Heinrich Müller, Nuremberg, Germany

Application March 13, 1939, Serial No. 261,616
In Germany August 24, 1938

23 Claims. (Cl. 46—206)

This invention relates to a new and considerable improvement in traveling toys.

It consists in the provision of an arrangement for putting into operation different speeds for traveling forwards, for idle running and for traveling in reverse of the toy. According to this invention which is hereinafter described as applied to a toy motor car the putting into operation of fixed speed stages and the change-over from driving forward to driving in reverse and idle running is effected by one control lever. In this way it is possible with the invention to carry out similar control motions to those of a full size model with modern speed changing means, thus providing a cheap instructional toy for practising gear changes and the like. Moreover, more particularly in the case of toy motor cars, the appeal of the toy is greatly enhanced and the modes of playing with the toy are increased.

According to the present invention the putting into operation of the individual fixed speed stages, of the idle running and of the reverse is effected as in the full size model either step by step in the sequence from the lowest to the highest or, conversely, from the highest to the lowest speed, with and without the idle running stage. Besides this natural sequence, any of the fixed speeds, idle running and the reverse may be put into operation selectively. Idle running may be put in operation by a separate lever and means may be provided, which will prevent an inadvertent putting into operation of the reverse.

The invention shall now be more particularly described with reference to the accompanying drawings. These only show examples of a constructional form and relate to a toy motor car. The invention is however not restricted to this form.

In the drawings:

Fig. 1 is a partial longitudinal section through a toy motor car which is traveling forwards.

Fig. 2 is a plan view of Fig. 1.

Fig. 3 is a section on line A—B of Fig. 1, the second speed having been put in operation.

Fig. 4 is a section similar to that on line A—B of Fig. 1, after the first speed has been put in operation.

Fig. 5 is a section similar to that on line A—B of Fig. 1, the third gear having been put in operation.

Fig. 6 is a section similar to that on line A—B of Fig. 1, the fourth gear having been put in operation.

Fig. 7 is a partial section of Fig. 1, the reverse having been put in operation.

Fig. 8 is a section on line C—D of Fig. 7, the reverse having been put in operation.

Fig. 9 is a section on line C—D of Fig. 7 in another constructional form.

Fig. 10 is a partial section of Fig. 1, with the idle running gear in operation.

Fig. 11 is a section on line E—F of Fig. 10.

Fig. 12 is a section on line E—F of Fig. 10 with the control levers occupying a different position with respect to one another.

Fig. 13 is a section similar to that on line A—B of Fig. 1, a locking device for the reverse being provided.

Fig. 14 shows another position of the control members of Fig. 13 with respect to one another, with the reverse released.

Fig. 15 is a partial section like that of Fig. 1 with a different constructional form of levers, the gears being arranged for forward running.

Fig. 16 is a section on line G—H of Fig. 15, after the first speed has been put in operation.

Fig. 17 is a section similar to that on line G—H of Fig. 15, with the idle running in operation.

Fig. 18 is a section similar to that on line G—H of Fig. 15, with the reverse put in operation.

Fig. 19 is a section similar to that on line G—H of Fig. 15, with the second speed in operation.

Fig. 20 shows different apertures for the gate of the control lever.

Fig. 21 is a partial longitudinal section through the toy motor car in another constructional form.

Fig. 22 is a plan view of Fig. 21, with the parts arranged for forward running.

Fig. 23 is a part view of Fig. 22.

Fig. 24 is a further part view of Fig. 22.

Fig. 25 is a section on line J—K of Fig. 21, with the second speed in operation.

Fig. 26 is a similar section to that of Fig. 25 with the parts set for idle running.

Fig. 27 is a part view of the mechanism shown in Fig. 21, with the control lever in the position shown in Fig. 26.

Fig. 28 is a section similar to Fig. 25, with the reverse in operation.

Fig. 29 is a part view of the spring mechanism of Fig. 21, with the lever in the position shown in Fig. 28.

The body of the traveling toy to be described by way of example consists of the bottom plate 1 and in the constructional example shown as a toy motor car of body work 2. To the bottom plate 1 are attached by means of a transverse member 3 the steerable front wheels 4, 5 so as to

turn on the pins 6 and 7. The front wheels 4, 5 carry steering levers 8 and 9 which are connected together by means of the control bar 10 which is provided with rack teeth 11. In these teeth engages the steering pinion 12 which is journaled with one of its ends in a bent-up portion 13 of the bottom 1 and with its other end in a plate 14 which stands perpendicularly on the bottom 1. At its inner end the pinion 12 carries the steering wheel 15.

One rear wheel 16 is mounted loosely on the rear wheel axle 17 which serves as the driving axle and on which the other rear wheel 18 is fixed. The rear wheel 18 is driven by a spring mechanism of a kind known per se, which is built into the frame 19. The driving spring 20 is mounted on a shaft 21 which is provided with a square portion which carries the gear wheel 22. This gear wheel meshes with a pinion 23 which is connected with a shaft 24 which carries the gear wheel 25. The latter gear wheel engages in the pinion 27 which is mounted on the shaft 26. On this shaft 26 is also mounted a gear wheel 28. The latter wheel meshes in Fig. 1 and Fig. 2 with a pinion 29, the shaft 30 of which is journaled in a bow member 31 which is capable of swinging about the rear wheel axle 17. The rear wheel axle 17 carries the pinion 32, by means of which the power of the spring is transmitted to it and consequently to the driving wheel 18 which is fixed on it. In the swingable bow member 31 is also journaled a pinion 33 which is also in mesh with the pinion 32 and the significance of which will be referred to later.

Besides the pinion 29, the gear wheel 28 also meshes with a pinion 35 mounted on the shaft 34. The shaft 34 also carries a crown wheel 36 which is in engagement with a pinion 37 mounted on the shaft 38. The shaft 38 is journaled in a bearing angle 39 provided on the frame 19 and in the plate 14. The shaft 38 carries at its other end a crank pin 40. This crank pin engages in the slot 41 of a swingable element 42. The latter is capable of swinging or oscillating on a pin 43 on the lever 44 which is mounted so as to be capable of turning at 45 on the plate 14. The lever 44 has a lug 46 which engages in the slot 47 of a cranked part 48 of a lever 49, so as to slide therein. The lever 49 is mounted so as to be capable of turning at 50 on the plate 14. It is provided with a slot 51, in which a pin 52 with a spring plate 53 slides, whereby the lever 49 is pressed against the plate 14 in such a manner that it cannot become unintentionally displaced. The lever 49 also has a slot 54, in which the control bar 55 slides, which is mounted with its forward end 56 so as to be capable of swinging in the bent-up portion 13 of the bottom 1. The forward end 56 which is bent over engages in a slot 57 provided in a lug 58 arranged on the bent-up portion 13. At its other end the lever 55 carries a manipulating knob 59.

There is also pivoted on the plate 14 at 60 a lever 61. This lever has notches 62 and 63 which are separated from one another by a cam 64. On the other side of the notch 63 is a cam 65 which has a flat depression 66 at its upper end. The lever 61 is also provided with an extension 67, against which is adapted to bear a lever 69 which is pivoted at 68 to the plate 14 and which carries a handle 70 projecting out of the toy. The motion of this handle is limited by a stop 87.

Finally, the lever 61 has a slot 71, in which a 75

lever 72 is guided with a bent over portion 73. This lever engages through a slot 74 in the plate 14 and is pivoted at 75 on the frame 19 of the casing of the driving mechanism. The lever 72 5 has a surface 76, against which an extension 77 is pressed by a spring 78 which is fixed to the bottom 1 of the traveling toy. The extension 77 is provided on the frame 31.

The bar 55 engages through an opening in 10 the plate 14, which opening consists of a transverse slot 79 having at its two ends a vertical slot 80, the ends of which bear the reference numerals 81 and 82, and a vertical slot 83, the 15 ends of which bear the reference numerals 84 and 85. From the vertical slot 83 a slot 86 leads at an inclination downwards.

The toy is also provided with a brake lever 88 which is pivoted on the frame 19 of the spring mechanism at 89 and carries a projection 90 20 which, when the lever 88 is pushed forward, bears against the front side of the pinion 37 and thereby exerts a braking action on the spring mechanism.

The control device illustrated in Figs. 1 to 12 25 acts in the following manner:

After the spring 20 has been wound up, the 30 brake lever 88 is swung backwards, so that its projection 90 releases the pinion 37. This enables the spring mechanism to run down. The lever 35 55 is thereupon brought into one of the slots 79, 80, 83, 86, according to the way in which the traveling toy is wished to move. This shall now be described in detail.

When, as shown in Fig. 3, the lever 55 is placed 35 in the slot end 86 of the slot 83, it will enter the notch 63 of the lever 61. The latter is held through the action of the spring 78 by means of the lever 72 in its topmost position. It is thus not influenced by the control lever 55. On the 40 other hand the lever 49 is brought by the guiding of the control lever 55 in the slot 54 into a definite position which is transmitted by way of the pin 46 to the lever 44, on which the swinging lever 42 is mounted. The point of rotation 43 of this swinging lever is thereby brought into a 45 quite definite position with respect to the crank pin 40, so that its swinging motion exerts a definite reaction on the running down of the spring-actuated mechanism.

On the control lever 55 being then brought 50 into the position shown in Fig. 4, that is to say into the end 84 of the slot 83, the lever 61 will remain uninfluenced in this position as well. On the other hand the position of the lever 49 55 will, through the control lever 55 being guided in the slot 54, be changed, whereby the pivotal point 43 of the swinging body 42 is brought by way of the lever 44 to a different distance from the crank pin 40. In the position shown in Fig. 4 the crank 40 and the pivotal point 43 have come closer together than was the case in the position shown in Fig. 3, so that the swinging body 42 is given a greater amplitude of swing and consequently exerts a greater braking action 60 on the driving mechanism. This mechanism and consequently the traveling toy will therefore run more slowly.

When however the control lever 55 is brought 65 into the position shown in Fig. 5, that is to say into the end 81 of the slot 80, the lever 61 will again for the time being remain uninfluenced. The lever 49 however will move into another position, whereby through the intermediary of the lever 44 the pivotal point 43 of the swinging member 42 is moved further away from the crank

pin 40. The influence of the swinging member 42 on the spring-actuated mechanism is thus less.

In the position shown in Fig. 6 the control lever 55 is placed in the end 82 of the slot 80. By this means the lever 44 is forced by way of the lever 49 so far downwards that the crank pin 40 comes entirely out of engagement with the slot 41 of the swinging body 42, so that the latter no longer influences the spring-actuated mechanism and the latter can thus run un- 10 hindered.

The illustrations with the speed arrangements embodied by them thus correspond to the four speeds of a motor car, so that change speed manipulations can easily be practiced. Thus, Fig. 3 corresponds to the second speed, Fig. 4 to the first speed, Fig. 5 to the third speed and Fig. 6 to the fourth speed.

With the traveling toy according to the invention it is however also possible to practice 20 idle running and running in reverse. These constructional forms are illustrated in Figs. 7 to 9 (reverse) and in Figs. 10 to 12 (idle running).

Fig. 8 shows the position of the levers 49, 44, 61 for running in reverse. For causing the traveling toy to run backwards the control lever 55 is engaged in the slot 86. The lever is thereby positively engaged in the notch 62 of the lever 61 which is rocked about its pivotal point 60 into its lowest position. By this means the lever 72 which is guided in the slot 71 of the lever 61 is forced downwards in the slot 74 and rocks about its pivotal point 75. In this way the extension 77 is forced downwards in opposition to the action of the spring 78, so that the frame 31 which is rigidly connected with it is rocked about the shaft 17, until the pinion 33 supported in the frame 31 meshes with the gear wheel 25. By this means the direction of rotation of the pinion 32 and with it by way of the shaft 17 that of the driving wheel 18 is reversed, as Fig. 7 clearly shows. The traveling toy will thus run backwards.

As a motor vehicle travels slowly in reverse, the engagement of the control lever 55 in the slot 86 causes the lever 49 to be rocked to such an extent that by way of the lever 44 the pivotal point 43 of the swinging body 42 is brought as close as possible to the crank pin 40, so that through the great amplitude of swing of the swinging body 42 a powerful braking action on the spring-actuated mechanism will take place, as Fig. 8 clearly shows.

A modification of the lever arrangement shown in Figs. 3 to 6 and 8 is shown in Fig. 9. In this figure an additional tension spring 91 is fixed at 92 to the plate 14. This spring is attached at 93 to the lever 61 and seeks to draw the latter upwards. In this case the lever 72 bears against a surface 73 of the lever 61 solely through the pressure of the spring 78. The lever 72 is therefore connected to the lever 61 not, as shown in Figs. 3 to 6, positively, but operatively. This arrangement naturally operates in exactly the same way as the constructional examples shown in the previous figures.

In the arrangement shown idle running is possible in two positions which are indicated in Figs. 10, 11 and 12. On the control lever 55 being introduced into the slot 79, it will come into the depression 86 of the cam 85 of the lever 61. The lever 61 is thereby forced downwards about its pivotal point 60 to such an extent that the lever 72 which is guided in the slot 71 of the lever 61, by being rocked in accordance with its mo-

tion in opposition to the action of the spring 78, brings both the pinion 29 and also the pinion 33 out of engagement with the wheels 28 and 25 respectively. The spring-actuated mechanism is thus entirely uncoupled from the driving axle 17. At the same time the lever 49 influences, in the manner already described, by way of the lever 44 the position of the pivotal point 43 of the swinging member 42 with respect to the crank pin 40 and thereby exerts a braking action on the spring-actuated mechanism.

For obtaining slow idle running, the control lever 55 may also be introduced into the upper part of the slot 86, as shown in Fig. 12. The position of the lever 61 is the same as in Fig. 11. The lever 49 however is in Fig. 12 rocked further to the right, so that by way of the lever 44 the pivotal point 43 of the swinging member 42 is brought closer to the crank pin 40, causing the braking effect of the swinging member 42 on the spring-actuated mechanism to be stronger.

In order to enable the idle running position to be effective even when the speeds are in the operative position, all that is required is to depress the handle 10. By way of the lever 69 which is connected to it and the extension 67 of the lever 61 the latter is swung into the position shown in Figs. 11 and 12, finding an abutment against the pin 87. This makes impossible a further rocking of the lever 61, which would bring it into the position of Fig. 8 and thereby put the reverse in operation. On the idle running being put in operation by way of the levers 69, 10, the distance of the pivotal point 43 of the swinging member 42 from the crank 40 remains that corresponding to the speed which at the time is in operation.

In the constructional form shown in Fig. 10 the control lever 55 consists of a two-armed lever, the part 55a of which is supported in a ball and socket joint 158 on the plate 14, whilst the part 55 engages in the slot 54 of the lever 49.

In the arrangement of the parts shown in Figs. 13 and 14 there is provided in addition to those of the previous figures a locking arrangement for the reverse, so that the latter cannot be put in operation without actuating the locking means. For this purpose the lever 61 has a special formation. It is pivoted in the same way as in the other figures at 60 to the plate 14. At one end it has an extension 94. At the other end is a bent over portion 95 which slides in a slot 96 of the plate 14 and acts merely as a guide. It is also provided with a locking projection 102 which is capable of covering the slot 86. In the example shown in Figs. 13 and 14 the lever 72 is connected operatively with the lever 61 by the spring 78.

On the plate 14 is also pivoted at 97 a lever 98 provided with a handle 99 which projects outwards beyond the body work of the toy. The lever 98 has a bent over portion 100 which is capable of pressing against the lever 61. It is also provided with a shoulder 101 which may be brought to bear against the extension 94 of the lever 61.

The arrangement operates as follows:

When as shown in Figure 13, the control lever 55 is for instance in the end 84 of the longitudinal slot 83, this, as already described, determines a certain distance of the crank pin 40 from the pivotal point 43 of the swinging member 42. The lever 98 bears with its bent-over portion 100 against the lever 61. The locking

projection 102 shuts off the part 86 of the control slots. The control lever 55 can therefore not be introduced into the part 86, which would bring about the reverse.

In order to make this possible, the lever 98 must be pressed downwards by depressing the handle 99 until it strikes against the stop 103. By this means the lever 61 is carried along by the bent-over portion 100, until the projection 101 bears against the extension 94. Through this motion the lever 61 is swung still further downwards until the lever 72 is in the idle-running position shown in Figure 10. This, however, causes the locking projection 102 to uncover the slot 86 for the introduction of the control lever 55, so that the latter can now enter this slot. By this means the locking projection 102 and with it the lever 106 will be forced still further downwards, so that the lever 72 will come into the position shown in Figure 7 in the lower end of the slot 14. The toy will therefore run backwards. On the control lever 55 being introduced into one of the other control slots, the spring 78 acting by way of the lever 61 will also cause the locking lever 98 to be brought into the position shown in Figure 13, in which position it will by means of its projection 102 again lock the control slot 86 for the reverse.

In the constructional forms shown in Figures 15 to 20 there is provided in the place of the slot guide for the lever 55, shown in the previous figures, an opening in the plate 14. The mode of operation in this constructional form is per se the same as in the previous figures.

On the plate 14 is pivoted at 60 the lever 61, at 50 the lever 49 and at 45 the lever 44, to which latter the swinging member 42 is pivoted at 43. The lever 61 is in engagement with the lever 72 through the slot 11. The control lever 55 slides in the slot 54 of the lever 49.

The control lever 55 has a fixed collar 104 and a loose disc 105, between which a spring 106 is arranged, which presses the loose disc 105 against the lever 49 and consequently the latter against the plate 14, so that the lever 49, owing to friction between it and the plate 14 thus produced, is held in whatever position it happens to be in. The plate 14 has an opening 107, in which the control lever 55 can be brought into different positions. The opening 107 may have various forms, examples of which are shown in Figure 20. The speed positions are indicated by Roman numerals. The openings 107 may have recesses 108 and be provided with a slot 109 for idle running and reverse. The idle-running position is indicated by F and the reverse position by A.

In Figure 16 the position for the first speed is shown. In this position the control lever 55 is in the corner I of the opening 107. The lever 49 is thereby brought into a definite position, so that the crank pin 40 and the pivotal point 43 of the swinging member 42 will be at a definite distance from one another, as was described with reference to the previous figures. The pressure of the spring 106 cannot cause an unintentional displacement of the lever 49, even when the toy is running, as this lever is pressed firmly against the plate 14.

In Figure 17 the idle-running position is shown. The control lever 55 is in the corner of the opening 107, which is indicated by F. In this position the disc 105 forces the lever 61 a short way downwards, so that the lever 72 comes into

the position shown in Figure 10, in which the pinions 29, 33 are uncoupled from the wheels 28 and 25 respectively, so that the mechanism can run down freely. The edge of the opening 107 between the position I and F is parallel to the position of the slot 54 of the lever 49, as shown in Figure 16. In this way, on displacing the control lever 55 from the position I into the position F, the lever 49 is not influenced, so that the distance of the crank pin 40 from the pivotal point 43 of the swinging member 42, and consequently the braking of the spring mechanism remains the same.

Figure 18 shows the position of the levers after setting to reverse. The control lever 55 is in the corner opening 107, which is marked A. The disc 105 forces the lever 61 round its pivot 60 completely downwards, until the lever 72 strikes against the bottom end of the slot 14. It thus comes into the position shown in Figure 7, so that the wheel 33 meshes with the wheel 25, thus bringing about the reverse, as already described above.

In the position shown in Figure 19, in which the control lever 55 is in the corner II of the opening 107, the second speed is in operation. In the constructional form shown in this figure the lever 49 is provided with an open guide 110, which is bridged over by a spring 111. This spring is inserted in the lever 49 at 112, and presses against the control lever 55 with such an amount of friction that an undesired displacement of the control lever is not possible. The mode of operation is the same as that described in the other figures.

In Figures 21 to 29 another constructional example of the invention is illustrated. This traveling toy consists of the bottom plate 1, and in the constructional example illustrated, of body work 2. To the bottom plate 1 are attached with a reverse member 3 the steerable front wheels 4, 5 so as to be capable of turning on the pins 6 and 7. The front wheels 4, 5 carry steering levers 8 and 9, which are connected together by means of the control bar 10 which is provided with rack teeth 11. In the teeth 11 engages the control pinion 12 which is journaled with one end in a bent-up portion 13 of the bottom 1 and at its other end in a plate 14 which is perpendicular to the bottom 1. The pinion 12 carries at its inner end the steering wheel 15.

One rear wheel 16 is mounted loosely on the rear wheel axle 17 which serves as the driving axle and on which the other rear wheel 18 is fixed. The rear wheel 18 is driven in a known manner by a spring-actuated mechanism which is built into the frame 19. The driving spring 20 is mounted on the shaft 21 which is provided with a square part and carries the gear wheel 22. The latter meshes with a pinion 23 which is connected to a shaft 24 which carries the gear wheel 25. The gear wheel 25 engages in the pinion 27 mounted on the shaft 26. On the shaft 26 is also mounted a gear wheel 28. The latter wheel meshes in Figures 21 and Figure 22 with a pinion 29, the shaft 30 of which is journaled in a rockable bow member 31. This bow member is mounted to rock on the driving shaft 17. The driving shaft carries the pinion 32, from which the power of the drive is transmitted to the driving shaft 17 and consequently to the driving wheel 18. In the rockable bow member 31 there is also journaled a pinion 33 which is also in engagement with the pinion 32. This

arrangement brings about the forward, backward and idle-running of the driving wheel 18, in the manner already described above.

The gear wheel 28 besides meshing with the pinion 29 also meshes with a pinion 35 mounted on the shaft 34. On the shaft 34 is also mounted a gear wheel 113 which meshes with the pinion 114 of a shaft 115. The shaft 115 is provided with a slot 116, in which by means of the pin 117 a braking vane 118 is pivotally supported. On the shaft 115 is also provided a sleeve 119 which is capable of being displaced in the axial direction and carries a flange 120. Around the flange 120 engages a fork 121 which is mounted on the bent-over portion 122 of a lever 123. The latter is held on the plate 14 by means of the pins 124 and 125 which engage in corresponding slots 126 and 127 of the lever 123 and is also held by a bent-over portion 128. Owing to this mode of mounting, it can slide parallel to the slots 126, 127. The lever 123 is provided with the control slot 129 having an inclined surface 130. This control slot is open at 131 and is provided in this opening with inclined surfaces 132 and 133.

On the plate 14 is also fixed a spring 134 which is attached at its other end at 135 to the lever 123. This spring seeks to force the lever 123 to the left in Figures 25, 26, 28.

Finally there is pivoted to the plate 14 at 136 a lever 137 having the two arms 138 and 139. The arm 139 has a bent-over portion 140, with which it is guided in a slot 141 of the plate 14. Its end acts on a lever 142 which is taken through a slot 143 of the plate 14. The lever 142 has a stirrup part 144 which is supported in the frame 19. On the lever 142 is fixed a helical spring 145, the end 146 of which bears against a projection 147 which is fixed to the frame 31. To the stirrup part 144 is also fixed a tension spring 148, the other end of which is attached to the frame at 149 and which counteracts the action of the helical spring 145. The control arrangement is actuated by the control lever 55 which is provided with the knob 59.

In the plate 14 is also provided an H-shaped opening consisting of the horizontal part 150 and the vertical part 151 with its ends 152 and 153, and of the vertical part 154 with its ends 155 and 156. In the middle of the horizontal part 150 a notch 157 is provided.

The arrangement operates as follows:—

In Figure 25 the second speed is for instance in operation. The control lever 55 is in this position in the part 153 of the vertical slot 151. It bears against the bottom end of the opening 129, so that the lever 123 is displaced to the right in opposition to the action of the spring 134. In this way the sleeve 119 is pushed by means of the control fork 121 and the flange 120 a short distance forward, as shown in Figures 22 and 23. On the shaft 115 turning through the action of the spring-actuated mechanism, the trapezoid-formed braking vane 118 is given a certain amplitude of swing, which has a braking effect on the running down of the mechanism.

In this position the lever 127 is not influenced by the control lever 55. It is forced downward by way of the lever 142 and through the action of the springs 146 and 148, so that, as shown in Figure 21, the pinion 29 meshes with the gear wheel 28. The driving wheel 18 is thus arranged to run forward.

On the control lever 55 being brought into the part 152 of the opening 151, it is displaced to

the left by the action of the spring 134. By this means the sleeve 119 is drawn further back in the described manner by means of the lever 123 and the fork 121. It thus comes into the position shown in Figure 24. The vane 118 is completely liberated and can thus perform its greatest swinging motion, so that in this way it applies the strongest braking action to the mechanism.

On the control lever 55 being brought into the position shown in Figure 26, it will lie in the opening 157 of the plate 14. It will thus simultaneously lift the lever 137 with its arm 139, and consequently at the same time the lever 142, so that as shown in Figure 27, owing to the corresponding swinging motion of the frame 31, the wheels 29 and 33 will come out of engagement with the wheel 28 and the wheel 25 respectively. The mechanism can then run down freely. This position therefore constitutes the idle-running position.

On the control lever 55 being brought into the end 155 of the vertical slot 154, as shown in Figure 28, the lever 137 is forced by the control lever 55 by means of the arm 138 completely to the right, so that the arm 139 lifts the lever 142, whereby the frame 31 is rocked to such an extent that the wheel 33 comes into engagement with the wheel 25. This position corresponds to the reverse, as shown in Figure 29.

At the same time the lever 123 is forced completely to the left and consequently the sleeve 119 is completely drawn back by means of the fork 121 and the flange 120, as shown in Figure 24, so that a strong braking action is exerted by the vane 118 on the spring-actuated mechanism.

On the control lever 55 being brought into the part 156 of the vertical slot 154, the lever 138 will, as will be seen from Figure 28, move back into the position shown in Figure 25. The forward running state is thus again brought about by the lever 142. The position of the lever 123 is the same as in Fig. 28, so that the slowest speed, that is the first speed, without traveling forward is in operation.

On the control lever 55 coming into the end 152 of the vertical slot 151, the lever 123 will be drawn entirely to the left and the sleeve 119 completely pulled forward by means of the flange 120 and the control fork 121, so that the vane 118 can no longer perform any swinging motion. The top speed of the traveling toy is thus in operation.

What I claim is:

1. A traveling toy comprising a wheel mounted body, a driving motor supported by said body, a driving connection between said motor and one of the wheels of the body, a speed governor operable by said motor and including a member mounted to perform swinging movements of variable amplitude, and means for adjusting said governor to vary the speed of the motor and the wheel mounted body, said means for adjusting the governor including a member having an opening therein and a manually operable lever movable into various positions in said opening.

2. A traveling toy comprising a wheel mounted body, a driving motor supported by said body, a driving connection between said motor and one of the wheels of the body, a speed governor operable by said motor and including a member mounted to perform swinging movements of variable amplitude, and means for adjusting said governor to vary the speed of the motor and the wheel-mounted body, said speed governor in-

cluding a shaft driven by said motor, said swinging member being pivoted to said shaft and adapted to swing outwardly in only one direction therefrom, an adjustable sleeve into which the centrifugal member is withdrawn for varying the amplitude of swinging movement of the centrifugal member, said sleeve being adjustable by said adjusting means.

3. A traveling toy comprising a wheel mounted body, a driving motor supported by said body, a driving connection between said motor and one of the wheels of the body, a speed governor operable by said motor and including a member mounted to perform swinging movements of variable amplitude, and means for adjusting said governor to vary the speed of the motor and the wheel-mounted body, said speed governor including a shaft driven by said motor, said swinging member being pivoted to said shaft and adapted to swing outwardly in only one direction therefrom, an adjustable sleeve into which the centrifugal member is withdrawn for varying the amplitude of swinging movement of the centrifugal member, said adjusting means including a fork engaging said sleeve for adjusting the latter.

4. A traveling toy comprising a wheel mounted body, a driving motor supported by said body, a driving connection between said motor and one of the wheels of the body, a speed governor operable by said motor and including a member mounted to perform swinging movements of variable amplitude, and means for adjusting said governor to vary the speed of the motor and the wheel-mounted body, said speed governor including a shaft driven by said motor, said swinging member being pivoted to said shaft and adapted to swing outwardly in only one direction therefrom, an adjustable sleeve into which the centrifugal member is withdrawn for varying the amplitude of said swinging movement of the centrifugal member, said adjusting means including a spring actuated lever for adjusting said sleeve.

5. A traveling toy comprising a wheel mounted body, a driving motor supported by said body, a driving connection between said motor and one of the wheels of the body, a speed governor operable by said motor and including a member mounted to perform swinging movements of variable amplitude, and means for adjusting said governor to vary the speed of the motor and the wheel-mounted body, said adjusting means including a manually adjustable lever mounted for movement in a direction perpendicular to its axis and a second lever actuated by the first lever and co-acting with said speed governor.

6. A traveling toy comprising a wheel mounted body, a driving motor supported by said body, a driving connection between said motor and one of the wheels of the body, a speed governor operable by said motor and including a member mounted to perform swinging movements of variable amplitude, and means for adjusting said governor to vary the speed of the motor and the wheel-mounted body, said adjusting means including a manually adjustable lever and a second lever actuated by the first lever and co-acting with said governor, a plate on said body supporting the second mentioned lever, and spring means co-acting with the manually operable lever and resiliently pressing the second mentioned lever against said plate.

7. A traveling toy comprising a wheel mounted body, a driving motor supported by said body, a driving connection between said motor and one

of the wheels of the body, a speed governor operable by said motor and including a member mounted to perform swinging movements of variable amplitude, and means for adjusting said governor to vary the speed of the motor and the wheel-mounted body, said adjusting means including a manually adjustable lever mounted for movement in a direction perpendicular to its axis and a second lever actuated by the first lever and co-acting with said speed governor, and spring means normally pressing the manually operated lever against the second mentioned lever.

8. A traveling toy comprising a wheel mounted body, a driving motor supported by said body, a driving connection between said motor and one of the wheels of the body, a speed governor operable by said motor and including a member mounted to perform swinging movements of variable amplitude, and means for adjusting said governor to vary the speed of the motor and the wheel-mounted body, said adjusting means including a manually operable lever and a second lever connected with the governor and having a slot therein guiding the movement of said manually operable lever.

9. A traveling toy comprising a wheel mounted body, a driving motor supported by said body, a driving connection between said motor and one of the wheels of the body, a speed governor operable by said motor and including a member mounted to perform swinging movements of variable amplitude, and means for adjusting said governor to vary the speed of the motor and the wheel-mounted body, said driving connection including a member movable to an inoperative position to interrupt driving connection between said motor and said body wheel, and means controlled by said adjusting means to move said member to said inoperative position.

10. A traveling toy comprising a wheel mounted body, a driving motor supported by said body, a driving connection between said motor and one of the wheels of the body, a speed governor operable by said motor and including a member mounted to perform swinging movements of variable amplitude, and means for adjusting said governor to vary the speed of the motor and the wheel-mounted body, said driving connection including means normally occupying a position to effect forward driving movement of the body and movable into two other positions to interrupt driving connection between said motor and said body wheel and to reverse the direction of movement of the wheel mounted body, and a lever controlled by said adjusting means to shift said movable means into its several positions.

11. A traveling toy comprising a wheel mounted body, a driving motor supported by said body, a driving connection between said motor and one of the wheels of the body, a speed governor operable by said motor and including a member mounted to perform swinging movements of variable amplitude, and means for adjusting said governor to vary the speed of the motor and the wheel-mounted body, said driving connection including a train of gear wheels and a pivoted member supporting certain of said gear wheels and movable from a normal forward driving position to two other positions to interrupt driving connection between said motor and said body wheel and to drive the wheel mounted body in the reverse direction, and means controlled by said adjusting means to effect adjustment of said member.

12. A traveling toy comprising a wheel mounted

ed body, a driving motor supported by said body, a driving connection between said motor and one of the wheels of the body, a speed governor operable by said motor and including a member mounted to perform swinging movements of variable amplitude, and means for adjusting said governor to vary the speed of the motor and the wheel-mounted body, said driving connection including a train of gear wheels and a pivoted member supporting certain of said gear wheels and movable from a normal forward driving position to two other positions to interrupt driving connection between said motor and said body wheel and to drive the wheel mounted body in the reverse direction, means controlled by said adjusting means to effect adjustment of said member, and spring means co-acting with said lever and normally retaining said member in its normal position.

13. A traveling toy comprising a wheel mounted body, a driving motor supported by said body, a driving connection between said motor and one of the wheels of the body, a speed governor operable by said motor and including a member mounted to perform swinging movements of variable amplitude, and means for adjusting said governor to vary the speed of the motor and the wheel-mounted body, said adjusting means including a manually operable member and a lever controlled by said member, said driving connection including means movable in two positions to interrupt driving connection between the motor and the body wheel and to reverse the driving connection between the motor and said driving wheel, a lever for actuating said movable means and operable by the first mentioned lever, and spring means normally maintaining operative relationship between the two levers.

14. A traveling toy comprising a wheel mounted body, a driving motor supported by said body, a driving connection between said motor and one of the wheels of the body, a speed governor operable by said motor and including a member mounted to perform swinging movements of variable amplitude, and means for adjusting said governor to vary the speed of the motor and the wheel-mounted body, means controlled by said adjusting means to render the driving connection inoperative, said adjusting means being movable to various positions while maintaining said driving connection inoperative to vary the idling speed of the motor.

15. A traveling toy comprising a wheel mounted body, a driving motor supported by said body, a driving connection between said motor and one of the wheels of the body, a speed governor operable by said motor and including a member mounted to perform swinging movements of variable amplitude, and means for adjusting said governor to vary the speed of the motor and the wheel-mounted body, said driving connection including movable means for disconnecting said motor from said body wheel and for reversing the direction of movement of said body wheel, a lever connected with said movable means, and cams on said lever actuated by said adjusting means for moving the movable means into its several positions.

16. A traveling toy comprising a wheel mounted body, a driving motor supported by said body, a driving connection between said motor and one of the wheels of the body, a speed governor operable by said motor and including a member mounted to perform swinging movements of variable amplitude, and means for adjusting said gover-

nor to vary the speed of the motor and the wheel-mounted body, said driving connection including movable means for interrupting and reversing the driving connection between the motor and said body wheel, a lever for actuating said movable means, said adjusting means including a slotted member and a manually operable member movable through the slot to a position to displace said lever and effect operation of said movable means, a projection on said lever normally limiting movement of said manually operable member, and means for displacing said lever to render said limiting means ineffect-

15 17. A traveling toy comprising a wheel mounted body, a driving motor supported by said body, a driving connection between said motor and one of the wheels of the body, a speed governor operable by said motor and including a member mounted to perform swinging movements of variable amplitude, and means for adjusting said governor to vary the speed of the motor and the wheel-mounted body, said driving connection including movable means for interrupting and reversing the connection between the motor and said body wheel, a double armed lever having one arm connected with said movable means, said adjusting means including a manually operable member engageable in certain positions 20 thereof with the other arm of said lever.

25 18. A traveling toy comprising a wheel mounted body, a driving motor supported by said body, a driving connection between said motor and one of the wheels of the body, a speed governor operable by said motor and including a member mounted to perform swinging movements of variable amplitude, and means for adjusting said governor to vary the speed of the motor and the wheel-mounted body, said adjusting means including a member having a substantially H-shaped slot therein, and a manually operable member movable through said slot to various positions for adjusting said governor.

30 19. A traveling toy comprising a wheel mounted body, a driving motor supported by said body, a driving connection between said motor and one of the wheels of the body, a speed governor operable by said motor and including a member mounted to perform swinging movements of variable amplitude, and means for adjusting said governor to vary the speed of the motor and the wheel-mounted body, said adjusting means including a member having an opening therein 35 provided with recesses and a manually operable lever movable into said recesses.

40 20. A traveling toy comprising a wheel mounted body, a driving motor supported by said body, a driving connection between said motor and one of the wheels of the body, a speed governor operable by said motor and including a member mounted to perform swinging movements of variable amplitude, and means for adjusting said governor to vary the speed of the motor and the wheel-mounted body, said driving connection including movable means for interrupting and reversing the driving connection between the motor and the body wheel, a lever controlled by said adjusting means for shifting said movable means, said lever including a bow-shaped part and two springs influencing said lever in opposite directions.

45 21. A traveling toy comprising a wheel mounted body, a driving motor supported by said body, a driving connection between said motor and one of the wheels of the body, a speed governor opera-

ble by said motor and including a member mounted to perform swinging movements of variable amplitude, and means for adjusting said governor to vary the speed of the motor and the wheel-mounted body, said driving connection including movable means for interrupting and reversing the drive to said body wheel, a lever for actuating said movable means and controlled by said adjusting means, and means independent of said adjusting means to actuate said lever.

22. A traveling toy comprising a wheel mounted body, and a driving motor supported by said body, a connection for forward and reverse driving between said motor and one of the wheels of the body movable to an inoperative position, a speed governor operable by said motor, and means for simultaneously adjusting said governor and said connection.

5 23. A traveling toy comprising a wheel mounted body, a driving motor supported by said body, a driving connection between said motor and one of the wheels of the body, a speed governor operable by said motor and including a shaft and a single centrifugal member pivoted to said shaft, and means for adjusting said governor to vary the speed of the motor and the wheel mounted body, and for rendering said speed governor inoperative, said adjusting means being solely 10 a sleeve movable axially of said shaft to variably limit the movement of said member from a position concentric with the axis of said shaft to various angular positions relative thereto.

15 HEINRICH MÜLLER.
